UNITED STATES PATENT OFFICE.

PIERRE L. LEISSE, OF BILLANCOURT, FRANCE, ASSIGNOR TO LOUIS RENAULT, OF BILLANCOURT, FRANCE.

CLEANING OF PUMP-STRAINERS.

1,198,560.

Specification of Letters Patent. Patented Sept. 19, 1916.

Application filed June 3, 1914. Serial No. 842,692.

To all whom it may concern:

Be it known that I, PIERRE LÉONARD LEISSE, citizen of the French Republic, residing at Billancourt, Department of the Seine, in France, have invented certain new and useful Improvements in the Cleaning of Pump-Strainers; and I do hereby declare the following to be a full, clear, and exact description of the invention, such as will 10 enable others skilled in the art to which it appertains to make and use the same.

The invention relates to a pump permitting of readily and rapidly cleaning the strainer during the operation of the pump 15 either by partly dismantling the strainer or automatically without any dismantling.

It is known that pump strainers, in particular when the liquids to be pumped contain matter in a suspended condition, become 20 clogged very rapidly. Their cleaning involves great difficulties owing to their position and very often it is necessary to stop the pump in order to effect this cleaning.

The strainer is constituted by a certain 25 number of vertical pipes the lower end portions of which form the rose or strainer proper, and are distributed along the periphery of a box immersed in the supply tank into which the suction pipe opens. The 30 openings through which each of the vertical tubes communicates with the common box, may be closed individually by means of valves which by placing the corresponding tube or pipe out of action, permit of the 35 cleaning operation without interfering with the operation of the pump either by dismantling the pipe or leaving it in place; the cleaning operation may be effected automatically or not.

40 The accompanying drawing shows various constructional forms of the device based upon the same principle.

In Figures 1 and 2, the strainer is composed of detachable tubes preferably disposed circularly around the suction pipe. 45 To this end, the suction pipe 1 is terminated at its lower end by a cylindrical box 2 formed with a plurality of apertures; above each of them tubes 3 are mounted the lower 50 portions of which are perforated to a certain height so as to form a strainer. At the lower portion of each of these tubes there is a seat adapted to receive a valve 4 which may be lowered and seated by means of a spindle 5, chain or any other suitable device.

The total section of the tubes 3 is reckoned in such a manner that if one of these tubes is cut out, the remainder have a sufficient cross-section to insure the supply of the pump. In this manner, each of the tubes 3 may 60 be successively withdrawn for cleaning purposes. To this end, before withdrawing the tube 3, the corresponding valve 4 is lowered so as to seat it by acting upon the spindle 5. The strainer can then be withdrawn and 65 cleaned and the same operation may be effected in connection with each tube 3 without interfering with the operation of the pump.

Figs. 3 and 4 show a more improved construction in which tubes forming the strain- 70 ers are fixed, the cleaning operation being effected in an automatic manner. In this case, the suction pipe 1 is mounted on a box 2 like in the previous case, but the tubes 3 being fixed, are connected at their upper part to a circular tube 6 by means of the valves 7. In each of the vertical tubes, a valve 4 is provided which can shut-off the tube at its lower part; this valve is operated 75 by means of the spindle 5 passing through the stuffing-box of the valve 7. Furthermore, the circular pipe is connected to the discharge of the pump and therefore receives water under pressure. During nor- 80 mal operation all the valves 4 are lifted and the tubes 3 operate like an ordinary strainer. When it is desired to clean one of the tubes, it is sufficient to lower the corresponding valve so as to cut off the suction of same. 85 Then the plug of the corresponding valve is turned so as to cause the pipe 6 to communicate with the interior of the tubes 3. The water under pressure being supplied through the pipe 6 penetrates the tube 3 and leaves 90 with force through the perforations of the strainer thus cleaning the latter. It is suffi- 95 cient to repeat the same operation successively on all tubes and the cleaning is effect- 100 ed automatically without any difficulty. It is obvious that if the number of the tubes and the section of their apertures are sufficient, the action of two or more tubes may be cut off simultaneously, instead of operating on one tube only.

In the device shown in Figs. 5 and 6, the cleaning is automatic and continuous. To this end, the tubes 3 instead of ending at their upper part into a circular pipe, are bent and have a horizontal portion 8. These 110

horizontal arms open into a central body in which there is a single valve disposed as shown in Fig. 5. This valve is operated for instance, by means of a bevel gearing and by 5 an electric motor or any other suitable device. The axis 10 of this valve supports a plate 11, one part of which is formed with a curved portion 12 the function of which is as follows: Each of the spindles 13 sup- 10 porting the valves 14 is terminated at its upper end by a hook 15 or similar member, bearing on the plate 11. When the hook of one of the valves bears on the curved portion 12 of the plate 11, the corresponding 15 valve is lowered. The valve 9 is keyed in such a manner that at this moment the corresponding tube 3 is placed in communication with the discharge of the pump through a pipe 16. It follows that when 20 the valve 14 is lowered and that therefore the corresponding tube 3 is obstructed at its upper part, water under pressure arrives immediately at the upper part of this tube and insures the cleaning thereof. The lat- 25 ter operation is therefore effected in a mechanical, automatic and continuous manner.

Finally, it must be pointed out that each of the three described apparatus is also 30 applicable in the case of immersed pumps and obviously to any kind of pump. In the case of an immersed pump, the suction pipe is dispensed with and the pipe for water under pressure insuring the clean- 35 ing of the strainers, may be located immediately at the beginning of the discharge.

I claim:

1. A pump strainer comprising a plurality of tubular perforated strainer ele- 40 ments, a common conduit to receive liquid drawn by the pump from the exterior of said elements through the perforations thereof and thence through the interior of the elements to said conduit, each element 45 being in communication with said conduit through an opening to permit the liquid to pass from the interior of the element to said conduit, means to close any one of said openings, and means to permit liquid

under pressure to be forced into the interior of and outwardly through the perforations of that strainer element whose communication with the conduit has been cut off by the closing of said opening, for the purpose described. 50

2. A pump strainer comprising a plurality of tubular perforated strainer elements, a common conduit to receive liquid drawn by the pump from the exterior of said elements through the perforations thereof and thence through the interior of the elements to said conduit, each element being in communication with said conduit through an opening to permit the liquid to pass from the interior of the element to said conduit, automatic means to close said openings in succession, and means to permit liquid under pressure to be forced into the interior of and outwardly through the perforations of that strainer element whose communication with the conduit has been cut off by the closing of said opening, for the purpose described. 60

3. A pump strainer comprising a plurality of tubular perforated strainer elements, a common conduit to receive liquid drawn by the pump from the exterior of said elements through the perforations thereof and thence through the interior of the elements to said conduit, each element being in communication with said conduit through an opening to permit the liquid to pass from the interior of the element to said conduit, automatic means to close said openings in succession, and means automatically operable to permit liquid under pressure to be forced into the interior of and outwardly through the perforations of each strainer element immediately after its communication with the conduit has been cut off by the closing of its opening. 70

In testimony whereof I affix my signature, in presence of two witnesses.

PIERRE L. LEISSE.
